UNITED STATES PATENT OFFICE.

CHARLES EDWARD HAVILAND, OF LIMOGES, FRANCE.

DESIGN FOR A CUP OR SIMILAR ARTICLE.

SPECIFICATION forming part of Design No. 32,869, dated June 26, 1900.

Application filed May 31, 1900. Serial No. 18,682. Term of patent 7 years.

To all whom it may concern:

Be it known that I, CHARLES EDWARD HAVILAND, a citizen of the United States, residing at Limoges, in the Republic of France, have 5 invented and produced a new and original Design for a Cup or Similar Article, of which the following is a specification, reference being had to the accompanying drawings, forming a part thereof, and in which—

10 Figure 1 is a side elevation of a cup bearing and incorporating my design, and Fig. 2 is a vertical section of same on the dotted line 2 2 of Fig. 1.

15 The leading features of my design consist of the shape of the body of the cup and the ornamental configuration thereon, substantially as shown.

In the drawings, A designates the cup, whose body has the downwardly and then inwardly inclined side surfaces lettered B C, respectively, and which body, adjacent to its upper edge, bears the scalloped ornamental scroll configuration D, as shown, said scroll configuration D being slightly in relief. 20

What I claim is—

25 The design for a cup or similar article, substantially as shown and described.

Signed at Paris, in the Republic of France, this 17th day of May, A. D. 1900.

CHARLES EDWARD HAVILAND.
